ATTYS.

UNITED STATES PATENT OFFICE.

FREDERICK H. MORSE, OF ST. LOUIS, MISSOURI, ASSIGNOR TO GUSTAVUS B. TAYLOR, OF ST. LOUIS, MISSOURI.

COMBINED CANE AND SEAT.

SPECIFICATION forming part of Letters Patent No. 768,882, dated August 30, 1904.

Application filed April 25, 1904. Serial No. 204,741. (No model.)

To all whom it may concern:

Be it known that I, FREDERICK H. MORSE, a citizen of the United States, residing in the city of St. Louis, in the State of Missouri, have 5 invented certain new and useful Improvements in a Combined Cane and Seat, of which the following is a full, clear, and exact description, reference being had to the accompanying drawings, forming part of this specification.

10 My invention relates to a walking-cane so constructed of sections that it may be opened into a condition so that the sections may receive the connection of a seat member on which the user of the cane may rest when weary.

15 Figure I is a perspective view of my combined cane and seat in open condition. Fig. II is an enlarged longitudinal section taken through the lower end of the cane in closed condition. Fig. III is a side view of a fragment of the upper part of the cane in closed condition. Fig. IV is a cross-section taken on line IV IV, Fig. III. Fig. V is a cross-section taken on line V V, Fig. III. Fig. VI is a perspective view of one end of the seat 25 member used in connection with the cane.

1 designates the body of my cane, which is split longitudinally to provide a staff 2, pivoted to the lower end of said body, as seen in Fig. I. The body of the cane is provided with 30 a head 3, and the split portion thereof extends from a point 4 below the upper end of the cane to a point 5 near its lower end. Fitted to the lower end of the cane-body is a ferrule 6, that contains a tip 7, preferably of rubber. The 35 cane-body being split to furnish the staff 2 renders both of said members throughout an extent corresponding to the length of the staff semicircular in cross-section, so that when the members are assembled the flat faces thereof 40 will rest against each other to complete the round symmetrical body of the cane. Secured to the lower end of the cane-body at the point of pivotal connection of the staff thereto are pivot-plates 8, that are united by a rivet 9, the 45 method of securing said pivot-plates being preferably that of providing ears 10, carried by the plates, as seen in Fig. I, full lines, and

Fig. II, dotted lines, which embrace the cane-body and staff.

11 designates a band encircling the cane-body at the upper end of its semicircular portion and provided with an eye 12, that is presented toward the staff-section 2 when said section is swung into open position.

13 is a band fitted to the upper end of the 55 staff-section 2 and provided with an eye 14, that is presented toward the cane-body, when said staff-section is in open condition.

15 designates a seat member of flexible material, such as canvas or leather, and to the 60 two ends of which are secured hooks 16 and 17, that are adapted for insertion into the eyes of the bands 11 and 13.

18 is a retaining-ring loosely fitted to the cane-body above the band 11 thereon, this 65 ring being adapted to embrace and hold the staff-section 2 to the cane-body when the parts are in closed condition, for which purpose the staff-section is continued slightly beyond the band 13 thereon to receive said ring, as 70 illustrated in Figs. I and III. By this arrangement the parts are held closely assembled when the article is being used as a walking-cane.

When it is desired to convert the article 75 into a seat, the retaining-ring 18 is slipped upwardly on the cane-body, as indicated by dotted lines, Fig. III, thereby freeing the staff-section 2, so that it may be swung outwardly away from the cane-body on its pivot-point. The hooks of the seat member 15 are then introduced into the eyes of the bands 11 and 13, thereby rendering the article suitable 80 as a rest upon which a person may be seated and supported. In the use of the article as a 85 seat the lower end of the cane-body rests upon the ground, and a person seated upon the seat member may sit sidewise thereon and maintain an upright posture by holding the head of the cane in the hand, or he may sit astride 90 of the seat member and hold the head of the cane or rest his elbows thereupon to maintain the article in upright position. When the article is used as a cane only, the seat

member may be readily disconnected from the cane-body and staff and carried in the pocket, so as to be handy in case it is desired to convert the article into a seat from time to time.

I claim as my invention—

1. In a combined cane and seat, the combination of a cane-body, a staff pivoted to the lower end of said body, a retaining-ring slidably fitted to the upper portion of said body, bands encircling said body and staff, and a seat member adapted to be detachably connected to said bands, substantially as set forth.
2. In a combined cane and seat, the combi-

nation of a cane-body, a staff pivoted to the lower end of said body, bands encircling said body and staff and provided with eyes, a seat member, hooks secured to the ends of said seat member and adapted to enter said band-eyes, and a retaining-ring slidably fitted to said cane-body and adapted to embrace said staff-section when in alinement with said body, substantially as set forth.

FREDERICK H. MORSE.

In presence of—

NELLIE V. ALEXANDER,
BLANCHE HOGAN.
